UNITED STATES PATENT OFFICE.

OTIS R. ANGELL, OF HAVERHILL, MASSACHUSETTS, ASSIGNOR TO HAMEL SHOE MACHINERY COMPANY, A CORPORATION OF MASSACHUSETTS.

EDGE SETTING AND BURNISHING MACHINE.

1,895,787.

Specification of Letters Patent. Patented Nov. 1, 1921.

Application filed June 6, 1918. Serial No. 238,570.

To all whom it may concern:

Be it known that I, OTIS R. ANGELL, a citizen of the United States, residing at Haverhill, in the county of Essex and State 5 of Massachusetts, have invented certain new and useful Improvements in Edge Setting and Burnishing Machines, of which the following is a specification, reference being had therein to the accompanying drawings.

10 This invention relates to machines for setting and burnishing the edges of shoe soles and in which a vibratory burnishing tool is employed. The present invention is directed more particularly to a burnishing tool for 15 the purpose described, such tool being provided with a knurled wheel adapted to engage the upper surface of the welt during the burnishing operation for imparting thereto the desired beaded finish.

20 While burnishing irons provided with beading wheels such as above described have long been known in the art, it has been found in practice that many such devices fail to perform their intended function in an 25 entirely satisfactory manner, principally by reason of the fact that the operating face of such a wheel lies in a plane substantially at right angles to the burnishing surface of the iron, the result being that pressure of 30 the work against the iron for securing the desired action of the latter fails to cause any pressure of the wheel against the welt such as is necessary to impart a beaded finish to the latter.

35 This invention seeks to overcome the above noted imperfections in operation of prior devices by so mounting the iron and the wheel carried thereby that the pressure of the wheel upon the welt surface shall 40 vary proportionally to the pressure of the sole edge against the burnishing face of the iron.

The invention thus contemplates the provision of a burnishing iron having associated therewith a movable support upon which is mounted the beading wheel, the parts being so relatively arranged that variations in pressure of the work against the iron causes a corresponding movement of 45 said support and the wheel carried thereby.

The invention further consists in providing a burnishing iron which is mounted for movement in a direction at right angles to the plane of its operating face, with a pivotally mounted bell-crank lever carrying 55 upon one arm a beading wheel of suitable form and having its opposite end arranged to contact with a fixed stop member, movement of the iron as a whole thus serving to produce a swinging of the bell-crank 60 lever and of the wheel carried thereby.

Other objects and advantages of the present invention, together with novel and desirable details of construction will be specifically described in the accompanying 65 specification and more particularly pointed out in the claims, reference being had to the annexed drawing for a full disclosure of a preferred embodiment thereof and in which,

70 Figure 1 is a side elevation, partly in section, showing the iron and the wheel-controlling mechanism, and

75 Fig. 2 is a front elevation of the same iron, certain parts being omitted for clearness of illustration.

1 is a vibratory support such as is commonly used for carrying the burnishing tool employed in edge setting machines of this type. This support is provided at 2 80 with a cylindrical spindle adapted for engagement with a socket 5 formed in a sleeve 4 integral with the block 3 which forms the burnishing iron proper, this iron having a burnishing surface 6 formed upon 85 the lower face thereof. 7 is a spring clip having mounted upon its lower end a roller 8 adapted for engagement with a shallow notch 9 formed in the forward face of the sleeve portion 4 of the iron, the spring clip being held in rigid engagement with the support 1 by means of a collar 10 and set screw 11, the latter having screw threaded engagement with a suitable opening in the support 1. The above arrangements for supporting and holding the iron are all 90 old and well known in the art, and need no further description.

95 3^a is a slot of key hole form cut in the front face of the block 3 and having a nar-

row upper portion and an enlarged lower portion, the latter extending into the burnishing face 6. Pivoted for swinging movement within said slot upon a transversely 5 extending pin 13 is a bell-crank lever 12, the arms 14 and 15 of said lever extending forwardly in substantially parallel relation, the arm 15 being the longer, however, of the two. Pivoted upon the extremity of 10 the arm 14, as by means of a pin 16 or other suitable device, is a rotary beading wheel 17, said wheel being provided with a bevel edge 18 which is knurled or corrugated for producing the desired finish 15 upon the surface of the welt.

The outer extremity of the arm 15 of the bell-crank 12 is adapted for engagement at its upper surface with the depending extremity of a stop member 19, the latter 20 being held in adjustably fixed position by passing through a suitable opening in the collar 10 wherein it is held by means of a set screw 20. As will be noted from inspection of Fig. 1 the socket 5 is of greater 25 depth than the length of the spindle 2, and by reason of the fact that the slot 9, in which the roller 8 rests, is shallow, the iron is permitted to have a slight vertical movement under pressure of the work against the 30 burnishing surface 6 thereof, such movement being limited by engagement of the top surface of the sleeve 4 with the shoulder 21 formed at the junction of the support 1 with the spindle 2, the parts, however, normally resting in the position shown in Fig. 35 1 in which the roller 8 is at the deepest part of the notch 9.

The operation of the device is as follows,—Upon engagement of the edge of the 40 shoe with the burnishing surface 6 and upon application of pressure to the shoe to secure the desired burnishing action, the iron tends to move slightly upward upon the spindle 2. In so moving upward the bell-crank lever 12 45 as a whole is also moved upward, but by reason of engagement of the lever arm 15 with the stop member 9, the arm 15 will be caused to swing downward to a slight extent, thereby also swinging the arm 14 downward 50 and with it the beading wheel 17. This movement of the beading wheel tends to cramp or pinch the same against the welt surface, the edge of the sole opposite the welt resting against the usual guard portion 55 22 of the iron, and thus a considerable pressure may be brought against the welt by the beading wheel to force the corrugations of the latter into the surface thereof. The above action insures the proper beading of 60 the welt under all conditions of employment of the device, and secures much greater uniformity in operation than has been heretofore produced when it has been attempted to perform the beading and burnishing operations simultaneously.

Having thus now described the invention with a preferred embodiment thereof and the mode of operation of the same what I claim as my invention and desire to secure by Letters Patent of the United States is,— 70

1. In a leather working device, in combination, a plurality of relatively movable tools constructed and arranged for simultaneous action upon the work, and means for causing one of said tools to move toward the 75 work as the pressure of the work against another of said tools is increased.

2. In an edge setting machine, in combination, an edge setting tool having a plurality of relatively movable elements constructed and arranged for simultaneous operation upon the work, and means acting to press one of said elements into contact with the work with a pressure increasing as that of the work against the other of said 85 elements increases.

3. In an edge setting machine, in combination, an edge setting tool comprising a burnishing element and a beading element, said elements being arranged for relative 90 movement, and means whereby pressure of the work against said burnishing element produces a proportional pressure between said beading element and the work.

4. In a shoe machine, in combination, an 95 edge-finishing tool comprising a burnishing surface and a beading wheel mounted for bodily movement with respect to said surface, and means for determining the relative positions of said surface and wheel in accordance with the pressure of the work against said surface.

5. In a shoe machine, in combination, an edge-finishing tool comprising a member providing a burnishing face, a lever pivoted 105 upon said member and having a beading wheel carried thereby for movement toward and from said face, and means for varying the relative positions of said member and lever in accordance with variations in pressure of the work against said surface.

6. In an edge setting machine, in combination, an edge iron having a burnishing face, means for supporting said iron for movement under pressure of the work in a 115 direction perpendicular to said face, a beading wheel mounted for bodily movement with respect to said iron, and means whereby movement of the iron under pressure of the work produces a corresponding relative 120 movement of said iron and wheel.

7. In an edge setting machine, in combination, an edge setting iron having a burnishing face, means supporting said iron for movement in a direction perpendicular to 125 said face under pressure of the work thereagainst, a lever pivotally mounted upon said iron and serving to support a beading wheel, and a fixed stop engageable with said lever whereby movement of the iron under pres- 130

sure of the work serves to move said wheel relatively to said burnishing face.

8. A shoe edge-finishing tool comprising a block provided with a burnishing surface upon one of its faces and having a slot formed in another face thereof, a lever pivoted for angular movement within said

slot and about an axis located at a point removed from said surface, and a beading wheel carried by said lever.

In testimony whereof, I have signed my name to this specification.

OTIS R. ANGELL.
